US0D1000594S

(12) United States Design Patent (10) Patent No.: US D1,000,594 S
(45) Date of Patent: * Oct. 3, 2023

(54) SINK STRAINER

(71) Applicant: Ningbo Wuhan Electronic Commerce Co., Ltd., Ningbo (CN)

(72) Inventor: Chengcheng Ding, Ningbo (CN)

(73) Assignee: Ningbo Wuhan Electronic Commerce Co., Ltd., Ningbo (CN)

() Term: 15 Years

(21) Appl. No.: 29/882,441

(22) Filed: Jan. 13, 2023

(30) Foreign Application Priority Data

Dec. 2, 2022 (CN) 202230808861.8

Primary Examiner — Karen S Acker

Assistant Examiner — Andrea Marie McKay

(57) CLAIM

The ornamental design for a sink strainer, as shown and described.

DESCRIPTION

FIG. 1 is a front perspective view of a sink strainer with the handle shown in an extended position, showing my new design;

FIG. 2 is a rear perspective view of the sink strainer with the handle shown in an extended position;

FIG. 3 is a front elevation view of thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front elevation view of the sink strainer with the handle shown in a non-extended position;

FIG. 10 is a front view of the sink strainer shown in a first position of use;

FIG. 11 is a front view of the sink strainer shown in a second position of use; and,

FIG. 12 is an enlarged detail view of the selected portion 12 shown in FIG. 1.

The long dash-short dash broken lines shown in FIG. 1 and FIG. 12 indicate cutoff boundaries for enlarged detail portion views and form no part of the claim.

1 Claim, 12 Drawing Sheets
